ABSTRACT

A volume control is provided for a reed organ having an air chamber, an air moving means, a reed and reed actuating means. The volume control features a temporarily deformable tongue which is cut out from a portion of the reed chamber, said tongue having a root portion integral with the reed chamber. The reed chamber and resultant cut out tongue is made of a plastic material having flexing properties therein.

VOLUME CONTROL FOR REED ORGAN

BACKGROUND OF THE INVENTION

This invention relates to volume controls, and more particularly to a volume control utilized in a reed organ.

It is well known that, in general, two types of volume controls are employed in reed organs; namely, those controls associated with either the intake or exhaust of air to and from the reed chamber, respectively. Heretofore, such volume controls of the prior art employed a multitude of components which not only resulted in increased labor and material costs, but also, at times, produced unwanted squeaking and hissing sounds, particularly when a change in the volume of air was effectuated. Such unwanted sounds resulted particularly in intake control systems wherein air was drawn into the reed chamber by an air moving means such as that of the impeller type.

SUMMARY OF THE INVENTION

Accordingly, it is an object of this invention to obviate the aforesaid undesirable difficulties resulting from the employment of the aforesaid volume controls of the prior art.

Further, it is an object of this invention to provide a volume control which is simple to manufacture, and at relatively low costs.

Broadly, the invention is concerned with an air intake volume control utilized in a reed organ which is provided with an air chamber, an air moving means, a reed and reed actuating means. The volume control includes a temporarily deformable tongue cut out from a portion of the reed chamber and having a root portion integral with the reed chamber. Means are provided for flexing the tongue from said reed chamber portion to permit any desired amount of air to be drawn into the chamber for pressurizing same and permitting a reed to be actuated by said actuating means.

In particular, the volume control is further provided with a minimal separation between the periphery of the tongue and the periphery of the reed chamber to preclude substantially no passage of air therethrough when the tongue is located in the original plane of the chamber from which it has been cut. Also, openings are provided in the air chamber at the terminal end portions of the tongue to permit air to be drawn therethrough to pressurize the chamber, which results in a reed being sounded in response to the reed actuating means to produce a tone at a constant low volume. Further, the volume control is provided with means for actuating same by either an operator's foot or knee.

DRAWINGS

FIG. 1 is an isometric view of the invention;

FIG. 2 is a bottom view of a reed chamber depicting one embodiment of the inventive volume control;

FIG. 3 is a partial elevational side view of the invention utilized in conjunction with an actuating means;

FIG. 4 is a partial elevation side view of the invention utilized in conjunction with another type activating means; and,

FIGS. 5, 6 and 7 are views of other embodiments of the invention.

DISCLOSURE OF THE PREFERRED EMBODIMENTS

The invention may best be illustrated by referring to FIG. 1 wherein there is depicted the inventive volume control which is integrally formed from and located within the bottom portion or base 10 of a reed air chamber, generally referred to as 11, wherein an impeller (not shown) or other similar type air moving means is located. Preferably, the inventive volume control is formed from and located at the bottom of a well 11a wherein the impeller is located, said well being an integral portion of a molded air chamber, as seen in FIGS. 3 and 4, which may be made of any suitable molding material, such as polystyrene.

The volume control, in general, is in the form of a flap or tongue 12, which is cut-out from base 10, and may be of any desired contour, as described in detail hereinafter. There is a minimal spacing or separation between periphery 12a of tongue 12 and periphery 10a of that portion of base 10 from which the tongue has been separated. In effect, as later described, when tongue 12 is in its normal at rest position, that is, when it is located in the original plane from which it has been cut from base 10, the separation or spacing between peripheries 10a and 12a is of such a small distance that it will preclude a minimal value of air, if any, to pass through said separation when the impeller is energized, thereby resulting in little, if any, undesirable hissing or squeaking sounds.

Located at the terminal portions 12b-12b of the separation or spacing between peripheries 10a and 12a are a pair of annular openings 16-16 which serve a dual purpose. Firstly, when tongue 12 is in its normal at rest position and the impeller is energized, sufficient air will be drawn from the atmosphere and through openings 16-16 into chamber 11 to permit a tone to be produced when an organ key 15 is depressed. Preferably, the openings are of such an area to permit that quantity of air to pass therethrough which is sufficient to pressurize chamber 11 to the extent necessary to permit a reed to be activated when a key is depressed. Accordingly, it can be seen that by varying the area of openings 16-16, any constant low volume of tone can be produced, as required, without any further activity by an operator with respect to the volume control.

Secondly, openings 16-16 serve as stress dispersal areas to prevent a tearing of tongue 12 when it is removed from its rest position and flexed as seen in FIG. 1, to permit additional air to pass therethrough for increasing the volume of tones to be produced, as later described.

Tongue 12 may be caused to flex and permit any desired amount of air to pass therethrough so as to pressurize the chamber and produce the desired volume of tone when a key is depressed. Tongue 12 may be controlled either by a foot or knee of a player of the organ. For example in FIGS. 1 and 3, there is depicted an opening 20 for receiving a rod 21 have at one end a hooked portion 22 which is inserted within opening 20. The other end of the rod is connected to a foot pedal (not shown) of a type disclosed in our U.S. Pat. No. 3,744,341. Accordingly, as the foot pedal is depressed, tongue 12 flexes from base 10 to permit air to be drawn therethrough by the impeller to pressurize the chamber.

In FIG. 4, there is shown another embodiment of the invention wherein it is capable of being knee operated.

As seen, a supporting arm 23 extends substantially perpendicular to and is integral with tongue 12. Alternatively, arm 23 need not be integral with tongue 12 but may be attached thereto by any conventional fastening means.

Uniquely, tongue 12 freely functions as a spring with uniform deformation therethrough as a result of the thickness and shape of the tongue together with the inherent flexing properties contained in the plastic material utilized. As seen in FIG. 2, tongue 12 includes a tip end 12c with diverging sides 12d-12d extending therefrom and terminating at a theoretical root end, as illustrated in phantom and referred to as 12e. It has been found that the degree of temporary deformation is dependant upon the angle of divergence between sides 12d-12d, as illustrated and referred to as Angle A. Accordingly, as the angle of divergence increases, temporary deformation of the tongue occurs towards top end 12c and, as the angle of divergence decreases, temporary deformation of the tongue occurs towards root end 12e. Therefore, it can be seen that by varying the contour of sides 12d-12d, temporary deformation can occur at any position along the tongue where desired.

Manifestly, the tongue can be of any desired control consistent with the performance required of certain impellers and reeds. For example, the contour of the sides of the tongue can vary such that the angle of divergence is not uniform throughout the tongue. Thus, in another embodiment of the invention, as disclosed in FIG. 5, the angle of divergence is constant near the tip portion 12c of the tongue and variant along the remaining portion thereof. Further, in another embodiment of the invention, as disclosed in FIG. 6, the angle of divergence is constant near the root portion 12e of the tongue and variant along the remaining portion thereof. Finally, in another embodiment of the invention as disclosed in FIG. 7, the widths of the tip end 12c and root end 12e of the tongue are variant, while the remaining portion thereof is constant so as to produce an even different angle of divergence during the temporary deformation of the tongue. From the foregoing, it now should become apparent that by forming varying contours of the tongue sides, root and end portions, varying desired finite metering of air is permitted to pass to the reed chamber.

We claim:

1. In combination with a reed organ having an air chamber, an air moving means, a reed and reed actuating means, a volume control, which comprises:

5 a temporarily deformable tongue cut out from a portion of the reed chamber and having a root portion integral with said reed chamber, and means for flexing the tongue from said reed chamber portion to permit any desired amount of air to be drawn into the chamber for pressurizing same and permitting a reed to be actuated by said activating means.

10 2. In a reed organ having a volume control, according to claim 1, wherein a minimal separation is provided between the periphery of the tongue and the periphery of the reed chamber portion from which the tongue has been separated to preclude substantially no passage of air through said separation and into the chamber when the tongue is located in the original plane of said chamber from which it has been separated.

15 3. In a reed organ having a volume control, according to claim 2, wherein an opening is provided in the reed chamber at each terminal end portion of said tongue to permit a preselected quantity of air to be drawn therethrough to pressurize the chamber and activate a reed to produce a tone at a constant low volume.

20 4. In a reed organ having a volume control, according to claim 3, wherein the reed chamber and resultant tongue separated therefrom is comprised of a plastic material having flexing properties therein.

25 5. In a reed organ having a volume control, according to claim 4, wherein the angle of divergence in the tongue during the temporary deforming thereof is related to the shape and thickness of the tongue.

30 6. In a reed organ having a volume control, according to claim 5, wherein the flexing means includes an integral arm extending substantially perpendicularly from the free end of said tongue.

35 7. In a reed organ having a volume control, according to claim 5, wherein the flexing means includes an opening located near the free end of the tongue, and foot actuated means connected to said tongue opening.

40 8. In a reed organ having a volume control, according to claim 5, wherein the reed chamber is provided with a well for receiving the air drawing means, and the tongue is separated from a portion of said well base.
